Primary Examiner — Tamara L Hahn(74) *Attorney, Agent, or Firm* — Benjamin D. Rotman; UB Greensfelder LLP(57) **CLAIM**

The ornamental design for a pallet skirt, as shown and described.

DESCRIPTION

FIG. 1 is a front perspective view of a pallet skirt, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of the pallet skirt of FIGS. 1-7, shown in a partially collapsed position in an environment of use; and,

FIG. 9 is a perspective view of the pallet skirt of FIGS. 1-7, shown in another partially collapsed position in an environment of use.

The figures include surface shading, which represents contour and not surface ornamentation.

1 Claim, 7 Drawing Sheets(56)
